MIXING DEVICE

Rudolph Guth, Cleveland, Ohio

Application January 13, 1930. Serial No. 420,570

9 Claims. (Cl. 299—84)

This invention relates to an improved mixing device adapted especially for the mixing of soap and water for suds.

The object of the present invention is to devise a container adapted to hold a supply of soap and having an attachment whereby there may be supplied to the same container the water for mixing the soap suds to be drawn off from the container.

10 Another object consists in the provision of such an attachment whereby there may be formed the soap suds or there may be supplied clear water, as may be required at any time for the thinning of the suds.

15 Other objects will appear from the following description and claims when considered together with the accompanying drawing.

Fig. 1 is a vertical sectional view of my improved device taken on line 1—1 of Fig. 2; Fig. 20 2 is a view taken on line 2—2 of Fig. 1.

The cask or drum or other form of container indicated by reference numeral 1 is provided with a false bottom 2 above which the space is intended for storing the soap supply, while below 25 the bottom 2, the space is intended to serve as a chamber for the soap suds which may be drawn off at any time desired through the spigot 3. The soap suds chamber is indicated by reference numeral 4, while the chamber for the soap supply 30 is indicated by the reference numeral 5. Extending upwardly through the main body of the container 1, and centrally thereof, is the perforated tubular member 6, the lower end of which is secured to the false bottom 2 which has an 35 opening provided centrally thereof so that the tubular member 6 communicates with the soap suds chamber 4. Thus, the soap is stored in the space 5 around the perforated tubular member 6 which extends substantially the full height of the chamber 5 and is open at the upper end as 40 well as the lower end thereof.

It is to be understood, of course, that the lower end of the drum 1 is closed by the usual form of bottom 7, while the upper end thereof is adapted 45 to be closed by a cover which may be removed therefrom. This cover may be in the form of a single head which may be removed in its entirety from the drum or it may consist of two parts, one of which is permanently attached to the drum 50 while the other central portion thereof may be attached to or removed therefrom at any time desired. In the present illustration, that portion of the head indicated by reference numeral 7 is permanently attached to the drum while the central portion thereof is removably attached to

the part 7. Formed as an integral part of the removable central part of the head, I have provided an attachment for the connection of a hose 8 and also a suitable form of valve for controlling the delivery of the water supply from 60 the hose. This valve is of a two-way form so that the water supply may be directed either down through the central port 9 or outwardly into the radially extending ports or channels 10, as will be explained. The port 9 which opens 65 down through the central portion of the casting in the removable part of the head, is so positioned that the water may be delivered therefrom down through the tubular member 6 and directly into the suds container 4 without contacting the soap supply in the chamber 5. The radiating channels 10 are connected at their 70 outer ends to the perforated annular tubular portion 11 from which the water will be sprayed on to the soap supply in the chamber 5 for the 75 purpose of forming suds to be delivered through the perforations in the tubular member 6 and therefrom into the suds container 4.

As a means of controlling the delivery of the water through the two ports just now referred to, I have provided the rotatably mounted valve member 12, which is formed with suitable ports therethrough for establishing the communications just mentioned. The port 13 extends diametrically and entirely through the valve member 80 12, and in the position indicated in Fig. 1, is adapted to extend between the two inner ends of the radiating channels 10. The ports 14 which extend approximately at 45° to the port 13, are adapted to communicate with the corresponding 85 channels 15 which are provided in the casting to which the hose 8 is adapted to be connected. Thus, with the valve in position indicated in Fig. 1, the water supply is adapted to pass through the hose 8, thence through the channels 15, the 90 ports 14, thence through the communicating port 13 to the radiating channels 10 and to the perforated sprinkling member 11, whence the water is delivered on to the top of the soap supply within the chamber 5. At this time, as will be 95 seen from Fig. 1, the valve member 12 closes the port 9 so that no water can be delivered directly therethrough into the tubular member 6. The water delivered from the sprinkling member 11 on to the soap supply in the chamber 5 as just now referred to, will dissolve a certain portion of the soap so as to form soap suds which will by gravity find their way through the perforations of the tubular member 6 and pass therethrough 100 downwardly into the chamber 4. As the suds are 105 110

being drawn off through the spigot 3, in case it should be found desirable to thin the consistency of the suds, this may be accomplished by changing the position of the valve member 12 so as to 5 close the passage through the channels 10 and to open the passage through the port 9. This may be done by rotating the valve member 12 through an angle of 90° so as to bring one end of the port 13 into communication with the upper end of the 10 port 9 while the other end of the port 13 will be closed at the diametrically opposite point by the closed wall portion of the valve structure. At the same time, one of the ports 14 will be brought into communication with one of the channels 15 15 while the other port 14 will be closed by means of the wall of the valve structure adjacent the upper end of the port 9. Thus, with the valve at the adjusted position referred to, communication will be established from the hose connection 8 20 through one of the channels 15, thence through one of the ports 14 and through the lower part of the port 13 and through the port 9 so as to deliver the clear water down through the tubular member 6 and into the suds chamber 4 for the 25 purpose of thinning the suds.

It is to be understood that the present disclosure is merely for purposes of illustration and that there may be devised certain variations and modifications without departing from the spirit 30 of the present invention as herein set forth. For instance, other forms of valve connections may be adopted for the purpose here intended, it being understood that the purpose of the present valve structure is to permit the delivery of the 35 water, either through the sprinkling device 11 for the formation of suds or through the port 9 and tubular member 6 in clear condition. The detailed structure of the casting including the valve structure may also be varied as may also the design and proportions of all of the other several 40 parts.

Thus, I have devised a comparatively simple 45 and efficient form of container within which the soap supply may be stored and to which there may be delivered a water supply for mixing with the soap within the same container for the making of suds to be drawn off as may be required. Also, with the present device, the consistency of 50 the suds may be varied, according to requirements. Although well adapted for the purpose of forming soap suds, it is to be understood that the present structure may be employed also for the mixing of any other ingredients which may be contained therein and supplied thereto.

The water as it enters the chamber 4, either 55 directly from the port 9 or through the perforations in the tubular member 6, will have a surging or churning action and there will thereby be effected a thorough mixing of the soap and the water so as to completely form the suds. Thus, chamber 4 may be regarded as a mixing chamber 60 as well as a reservoir for the suds.

A removable plug 1^a may be provided in the wall 65 of the drum 1, at a point just above the false bottom 2, so as to afford a means of determining whether the soap supply in the drum needs to be replenished.

Upon disconnection of the hose 8, a suitable 70 form of cap may be placed upon the upper end of the casting so as to exclude the air and dirt therefrom.

The usual pressure of the regular water supply 75 system is sufficient for the present device. The present device may be formed as a perma-

nent part of the drum or cask which may be re-filled from time to time as may be required.

What I claim is:

1. A mixing device comprising a single container having an upper compartment and a lower compartment, a perforated tubular means extending from said lower compartment up into said upper compartment, said perforated tubular means being the only means of communication between said upper and lower compartments and being so located laterally as to afford space to the side thereof, means for supplying a liquid directly and exclusively to said upper compartment space about said tubular means, whereby a soluble material may be contained in said upper compartment and outside of said tubular means and may be dissolved by the introduction of liquid thereto and the resulting mixture transmitted through the perforations of said tubular means and thence through said tubular means into said lower compartment, and means for dispensing the mixture from said lower compartment. 80

2. A mixing device comprising a single container having an upper compartment and a lower compartment connected only by a single centrally disposed perforated tubular member extending from said lower compartment up through substantially the entire extent of said upper compartment, means for supplying a liquid directly to either said upper compartment or directly 100 through said tubular member to said lower compartment, whereby a soluble material may be contained in said upper compartment and about said tubular member and may be dissolved by the introduction of liquid thereto and the resulting mixture transmitted through the perforations of said tubular member and thence through said tubular member into said lower compartment, or the liquid may be transmitted directly to said lower compartment, and means for dispensing 110 the mixture from said lower compartment. 105

3. A mixing device comprising a single container having an upper compartment and a lower compartment connected only by a single centrally disposed perforated tubular member extending from said lower compartment up through substantially the entire extent of said upper compartment, a single valve-controlled means for supplying a liquid either directly to said upper compartment or directly through said tubular member to said lower compartment, whereby a soluble material may be contained in said upper compartment and about said tubular member and may be dissolved by the introduction of liquid thereto and the resulting mixture transmitted 120 through the perforations of said tubular member and thence through said tubular member into said lower compartment, or the liquid may be transmitted directly through said tubular member to said lower compartment, and means for dispensing the mixture from said lower compartment. 125

4. A mixing device comprising a single container having an upper compartment and a lower compartment connected only by a single centrally disposed perforated tubular member extending from said lower compartment up through substantially the entire extent of said upper compartment, a single valve-controlled means arranged at the upper end of said tubular member 140 and having outlets for supplying a liquid to either said upper compartment or directly through said tubular member to said lower compartment, whereby a soluble material may be contained in said upper compartment and about said tubular 145 member. 130

150

member and may be dissolved by the introduction of liquid thereto and the resulting mixture transmitted through the perforations of said tubular member and thence through said tubular member into said lower compartment, or the liquid may be transmitted directly through said tubular member to said lower compartment, and means for dispensing the mixture from said lower compartment.

10 5. A mixing device comprising a single container having an upper compartment and a lower compartment connected only by a single centrally disposed perforated tubular member extending from said lower compartment up through substantially the entire extent of said upper compartment, a cover for said container, said cover having formed as part thereof a spray device for supplying liquid to said upper compartment, and said cover having also as part thereof a plain discharge connection for supplying liquid directly into the upper end of said tubular member for delivery to said lower compartment, a single valve carried by said cover and having means of communication with said spray device and said plain discharge connection for controlling the delivery of liquid in the aforesaid manner, whereby a soluble material may be contained in said upper compartment and about said tubular member and may be dissolved by the introduction of liquid thereto and the resulting mixture transmitted through the perforations of said tubular member and thence through said tubular member into said lower compartment, or the liquid may be transmitted directly through said tubular member to said lower compartment, and means for dispensing the mixture from said lower compartment.

6. A mixing device comprising a container having means for supporting the same upon the floor, said container having an imperforate partition dividing the same into upper and lower compartments, a perforated tubular member extending vertically of said upper compartment and so located laterally as to afford space to the side thereof so as to accommodate a soluble material in said space, said perforated tubular member constituting the only means of discharge from said upper compartment, means for supplying a liquid directly and exclusively to the soluble material in the upper compartment, whereby the soluble material may be dissolved by the introduction of liquid thereto and the resulting mixture transmitted through the perforations of said tubular member and thence through said tubular member, and valve means adapted to control the discharge from the container for dispensing the said mixture therefrom.

7. A mixing device comprising a single container having means for supporting the same upon the floor and having an upper compartment and a lower compartment connected only by a single perforated tubular member extending vertically from said lower compartment up through substantially the entire extent of said upper compartment and so located laterally as to afford space to the side thereof, a cover for said container, said cover having formed as part thereof a spray device for supplying liquid to said upper compartment, and said cover having also as part thereof a plain discharge connection for supplying liquid directly into the upper end of said tubular member for delivery to said lower com-

partment, a single valve carried by said cover and having means of communication with said spray device and said plain discharge connection for controlling the delivery of liquid in the aforesaid manner, whereby a soluble material may be contained in said upper compartment space about said tubular member and may be dissolved by the introduction of liquid thereto and the resulting mixture transmitted through the perforations of said tubular member and thence through said tubular member into said lower compartment, or the liquid may be transmitted directly through said tubular member to said lower compartment, and valve means provided in the lower compartment for controlling the discharge of the mixture therefrom.

8. A mixing device comprising a single container having means for supporting the same upon the floor and having a transverse partition dividing the interior of the container into upper and lower compartments, said compartments being connected by only a single, perforated tubular member extending vertically from an aperture in said partition up through substantially the entire extent of said upper compartment and so located laterally as to afford space to the side thereof, a cover for said container, said cover having formed as part thereof a spray device for supplying liquid directly and exclusively to said upper compartment, and said cover having also as part thereof a plain discharge connection for supplying liquid directly and exclusively into the upper end of said tubular member for delivery to said lower compartment, a single valve carried by said cover and having means of communication with said spray device and with said plain discharge connection for controlling the delivery of liquid in the aforesaid manner, whereby a soluble material may be contained in said upper compartment space about said tubular member and may be dissolved by the introduction of liquid thereto and the resulting mixture transmitted through the perforations of said tubular member and thence through said tubular member into said lower compartment, or the liquid may be transmitted directly through said tubular member to said lower compartment, and valve means provided in the lower compartment for controlling the discharge of the mixture therefrom.

9. A mixing device comprising a container for soluble material, the bottom of said container having a discharge opening therethrough and being otherwise imperforate, a perforated tubular member extending vertically within said container from the discharge opening and being so located laterally as to afford space to the side thereof, said tubular member constituting the only means of discharge from the space around the same, means for supplying a liquid directly and exclusively to said container space about the tubular member, whereby a soluble material may be placed in such container and outside of said tubular member and dissolved by the introduction of liquid thereto and the resulting mixture transmitted through the perforations of said tubular member and thence through said tubular member, or for transmitting the liquid directly into and through said tubular member, and means for controlling the discharge from the lower end of the tubular member.

RUDOLPH GUTH.
